(57) **CLAIM**

We claim the ornamental design for an electrical receptacle circuit board, as shown and described.

DESCRIPTION

FIG. 1 is a top plan view of the electrical receptacle circuit board showing our new design, the bottom plan view being a mirror image thereof;

FIG. 2 is a left side elevational view thereof;

FIG. 3 is a right side elevational view thereof;

FIG. 4 is a front elevational view thereof; and,

FIG. 5 is a rear elevational view thereof.
